CLAIM

The ornamental design for partially transparent IC card, as shown and described.

DESCRIPTION

FIG. 1 is an enlarged top, front and right side perspective view of partially transparent IC card showing our new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a bottom plan view thereof;

FIG. 8 is a greatly enlarged cross-sectional view thereof, taken along line 8—8 in FIG. 7.

FIG. 9 is an enlarged top, front and right side perspective view of a second embodiment of the partially transparent IC card;

FIG. 10 is top plan view thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a bottom plan view thereof;

FIG. 16 is a greatly enlarged cross-sectional view thereof, taken along line 16—16 in FIG. 15.

FIG. 17 is an enlarged top, front and right side perspective view of a third embodiment of the partially transparent IC card;

FIG. 18 is a top plan view thereof;

FIG. 19 is a front elevational view thereof;

FIG. 20 is a rear elevational view thereof;

FIG. 21 is a right side elevational view thereof;

FIG. 22 is a left side elevational view thereof;

FIG. 23 is a bottom plan view thereof;
FIG. 24 is an enlarged cross-sectional view thereof, taken along line 24—24 in FIG. 23;
FIG. 25 is an enlarged top, front and right side perspective view of a fourth embodiment of the partially transparent IC card;
FIG. 26 is a top plan view thereof;
FIG. 27 is a front elevational view thereof;
FIG. 28 is a rear elevational view thereof;
FIG. 29 is a right side elevational view thereof;

FIG. 30 is a left side elevational view thereof;
FIG. 31 is a bottom plan view thereof; and,
FIG. 32 is a greatly enlarged cross-sectional view thereof, taken along line 32—32 in FIG. 31.
The broken line drawings in FIGS. 1, 2, 7, 9, 10, 15, 17, 18, 23, 25, 26 and 31 are for illustrative purposes only and form no part of the claimed design.
